HEDGE SHEARS

Bernard C. Sharp, White Plains, N.Y., assignor to International Patent Research Corp., New York, N.Y., a corporation of New York
Original design application Aug. 6, 1965, Ser. No. 86,478.
Divided and this application May 13, 1966, Ser. No. 2,893

Term of patent 7 years

(Cl. D22—4)

FIG. 1

FIG. 2

FIG. 3

FIG. 4

FIG. 1 is a three-quarter perspective view of a pair of hedge shears showing my new design;

FIG. 2 is a top plan view thereof;

FIG. 3 is an end elevational view thereof as seen from the left of FIG. 2; and

FIG. 4 is a side elevational view thereof.

This application is a division of my earlier filed copending application Serial Number D-86,478, filed August 6, 1965.

I claim:

The ornamental design for hedge shears, as shown and described.
